WELL PUMP DYNAGRAPH

Walton E. Gilbert, Pasadena, and Sumner B. Sargent, Huntington Park, Calif., assignors to Shell Development Company, San Francisco, Calif., a corporation of Delaware, and Sargent Engineering Company, Los Angeles, Calif., a corporation of California, jointly

Application March 16, 1936, Serial No. 68,999½

8 Claims. (Cl. 265—2)

This invention pertains to reciprocating well pumps and is more particularly concerned with apparatus for recording the stroke and lifting force, and therefore the power, of such pumps on indicator diagrams traced within the well.

The usual practice in petroleum production has been up to the present to determine the stroke of an oil well pump and the forces acting at the pump from data obtained at the well head. These determinations, however, were often inaccurate, considerable errors being introduced by such factors as friction and/or the stretching of various mechanical parts connecting the pump at the bottom of the well with the recording apparatus at the well head.

It is therefore an object of this invention to provide a recorder device of a simple and rugged construction, which may be connected directly to the pump and lowered therewith into the well for recording on a chart the actual stroke of the pump and the forces acting at the pump as functions of the reciprocating motion of the pull rod actuating the plunger of the pump and of the elastic changes in length of said pull rod due to the alternating stresses to which it is subjected during pumping.

It is another object of this invention to provide a device recording the elastic changes in the length of a portion of the pull rod so located in the well that said elastic changes are due substantially only to the pumping forces exerted, any elastic changes due to the weight of the pull or sucker rods located below said portion being negligible as compared therewith.

It is a further object of this invention to provide a mechanical system of operation whereby the power developed by a pump may be continuously recorded on a chart at the pump for a plurality of operating cycles by means of a chart-feeding mechanism.

These and other objects and useful features of the invention will be understood from the following description taken with reference to the attached drawings, wherein:

Fig. 1 is a vertical view, partly in cross-section, diagrammatically showing one form of the present recording device.

Fig. 2 is a cross-section taken along the line 2—2 of Fig. 1.

Fig. 3 is a detailed view showing the type of indicator diagrams traced by means of the recorder.

Fig. 4 is a perspective view of the chart-feeding mechanism located at the well head.

Referring to Fig. 1, a tubing string 1 holds a

pump 27, provided with a check valve 28. A plunger 34 moves within the cylinder of the pump and is provided with a check valve 36. On the upward stroke of the plunger, the pump cylinder is filled by suction with the well liquid, valve 29 being open and valve 36 closed. On the downward stroke of the plunger, valve 29 is pressed against its seat, while valve 36 opens and admits the liquid inside the plunger 34, whence it is forced on the upward stroke, through passageways 33 and 32, inside the tubing 1 and upwards to the well head. It is understood that the pump plunger or piston, check valves, etc., form no part of the present invention and may be constructed in any desired manner, since the apparatus of the present invention may be used with practically any type of reciprocating pumps.

The pump barrel 27 is connected by means of screw threads 28 to the cover tube 24 of the recorder, which is thus mounted above the pump. Although in the preferred embodiment of Fig. 1, the recorder is shown directly above the pump, it is possible to mount the recorder at some distance above the pump. This distance should not, however, be too great in order that the elastic changes in the length of the pull rod, recorded in the manner described below, be not affected by the weight of the portion of the pull rod between the recorder and the pump. A pull rod 26, actuating the plunger and also forming a working part of the recorder, extends through cover tube 24 and is connected at its upper end to the string of sucker rods 2 by means of coupling 4. The sucker rods 2 extend to the well head and are there actuated by a motor or other suitable reciprocating means.

On the threaded portion 5 of the upper end of the pull rod 26 is mounted a ball bearing mechanism 8, held by a housing sleeve 10, which is free to rotate around the pull rod 26. The housing sleeve 10 is closed at the top by a bushing 3, and has at its lower end threads 7, holding a revolving tube 11, with two helical slots 9 cut in its outer surface. The revolving tube 11 fits inside the recorder's cover tube 24, which, as stated above, is supported at its lower end by the pump barrel. Lugs 12 are permanently set in the upper part of cover tube 24 and are adapted to slide along the helical slots 9 of revolving tube 11, so that any axial motion of the revolving tube 11 with regard to the cover tube 24 causes the tube 11 to rotate on the bearings 8 by means of which it is attached to the pull rod 26. It will be seen that the direction of the rotational motion of revolving tube 11 will reverse when the direc-

tion of the axial motion of pull rod 26 is reversed. The lower end of revolving tube 11 carries an adapter tube 13 provided with a marker, such for example, as a steel needle, or a diamond-pointed 5 stylus 20, or other marking means adapted to trace lines on a chart, such as a recording cylinder 22. The recording cylinder 22 is preferably made of copper or of a similar plastic or deformable material such, for example, as one 10 or several wrappings of a copper sheeting of 0.01 inch thickness. Cylinders made in this manner have the advantage of not being impaired or destroyed by contact with fluids, and may moreover be easily withdrawn from the recorder and 15 flattened out to facilitate the analysis of the record obtained.

The recording cylinder 22 is supported by a winged nut 17 carried on the threaded lower end 20 of pull rod 26. The winged nut and the recording cylinder are kept from rotating with regard to the cover tube 24 by the action of lugs 19 sliding in two opposite vertical slots 16 cut on the inner side of cover tube 24. Sometimes, it may be desirable to cut holes 21 near the bottom of 25 the cover tube 24 to provide for an easy inflow and outflow of oil and thus prevent the instrument to absorb energy by acting as a dashpot. The recording cylinder 22 slidably extends through a bushing 15 carried by the adapter tube 30 13, the purpose of this bushing being to center the revolving tube 11 and the recording cylinder 22 with regard to each other.

It is clear from the above description of the 35 cooperating parts of the present device that with every stroke of the plunger 34, actuated by the pull rod 26, both the recording cylinder 22 and the marker 20 move together axially since they are both attached to said pull rod 26. The action 40 of the lugs 19 sliding in vertical slots 16 prevents any rotational motion of the recording cylinder 22 with regard to the cover tube 24, while the action of the lugs 12 affixed onto tube 24 and sliding in the helical slots 9 causes the revolving tube 11 together with the adapter tube 13 and 45 the marker 20 to rotate with regard to the cover tube 24 and the cylinder 22, the point of the marker 20 tracing on the cylinder 22 horizontal lines 41 and 42 (shown in Fig. 3) of a length proportional to the travel of the lugs 12 in the 50 helical slots 9 or, in other words, to the stroke of the pull rod 26 and of the plunger 34.

The pull rod 26 is subjected during pumping to various stresses, such as the tension stress on the upward stroke, which causes changes in its 55 length on each reversal in the direction of its axial motion. The changes in length of the pull rod 26 between the points 17 and 5 where the recording cylinder 22 and the marker 20 are respectively attached thereto cause the recording 60 cylinder and the marker to be displaced axially with regard to each other. As shown in Fig. 3, this displacement is recorded as the distance between the horizontal line 41, traced by the marker on the recording cylinder during the upward 65 stroke of the plunger, and the horizontal line 42 traced during the downward stroke of the plunger. Since the stresses to which the pull rod is subjected are within the elasticity limits of the material of which it is made, the vertical distance 70 between lines 41 and 42 is proportional to the force acting on the plunger. Since the length of the lines 41 and 42, as explained above, is proportional to the stroke of the plunger, the area of the figure traced by marker 20 is proportional 75 to the work done at the pump during one

cycle of its operation. By calibrating the recorder in suitable units, the power developed by the pump may therefore be conveniently measured on the diagram obtained.

To obtain a displacement of the successive 5 records of individual cycles during a certain period of operation of the pump, the sucker rods 2 may be rotated at the surface, for example, after each cycle, or after any desired number of cycles. The rotation of the sucker rods 2 is 10 transmitted to the pull rod 26, and causes the winged nut 17, which is prevented from rotating by the lugs 19, to travel upwards on the screw threads of pull rod 3, the recording cylinder 22 being thereby raised by a certain amount 15 with regard to the stylus 20 for each successive cycle. The type of diagram obtained in this manner is shown at 47, Fig. 3.

The sucker rods 2 may be rotated either manually or automatically, for example, by means of 20 a device such as the Sargent rotor, shown in Fig. 4.

This rotor, which forms no part of this invention, is mounted at 51 on the end of the top 25 length 2 of the sucker rod string, attached to the walking beam 50 by means of a rod beam hanger 52. The rotor 51 is provided with a lever 53, connected with the walking beam by a chain 55. Due to the angular displacement of the rod beam hanger 52 with regard to the walking beam 50 30 during pumping, the chain 55 is stretched on each downward stroke and pulls up the lever 53, which in turn operates to rotate the sucker rods 54 by means of the rotor mechanism 51.

For example, during one run of the present recording device, the rotor moved the sucker rods through one-fifteenth of a turn during each downward stroke, and since the winged nut 17 had sixteen threads to the inch, the axial movement of the recording cylinder 22 with regard to 40 the marker 20 was about 0.0042 inch per cycle, such displacement being discernible on the record obtained.

It is understood that other means of rotating the rods may be used. For example, it has been 45 found that one set of readings may be set apart from the others by stopping the pump and rotating the rods manually, the stylus tracing a line 45 during this operation, as shown in Fig. 3.

It is understood that neither the above description nor the drawings illustrating a preferred embodiment of the present device should in any way be taken to limit this invention which is capable of many modifications falling within 50 the scope of the appended claims.

Thus, for example, the recording cylinder may be rotatably mounted on a bearing, while the marker may be provided with means preventing it from rotation, an indicator diagram similar to the one described above being obtained in this 55 case.

It is also possible to record the stroke of a pump directly by the axial movement of the marker, while causing the changes in length of the pull rod to rotate the chart and the marker 65 with regard to each other by amounts proportional to the forces applied to the pull rod.

Likewise, the chart feeding mechanism need not be controlled from the surface, but may be placed within the recorder, for example, in the 70 form of a clock mechanism adapted to displace the chart with regard to the marker.

Furthermore, should the changes in length of the pull rod be of insufficient magnitude to give a clearly readable record on the chart, a special 75

elastic link, comprising, for example, a strong and suitably calibrated spring may be inserted in the pull rod between the points of attachment of the chart and the marker to increase the amount 5 of their relative axial displacement with regard to each other during each operating cycle.

We claim as our invention:

1. In a device for recording the power of a reciprocating well pump comprising a pull rod 10 located in the well, and a motor reciprocating said pull rod in the well and causing elastic changes in its length, a chart and a marker supported by said pull rod, means for displacing the chart and the marker with regard to each other 15 by an amount proportional to the stroke of the pump, means for displacing the chart and the marker with regard to each other transversely to said last displacement by an amount proportional to the elastic change in length of the pull rod, 20 and means to record said displacements on the chart by the marker.

2. In a device for recording the power of a reciprocating well pump comprising a pull rod located in the well, and a motor reciprocating 25 said pull rod in the well and causing elastic changes in its length, a chart and a marker in contact with each other and attached at spaced points to said pull rod, means for displacing the chart and the marker with regard to each other 30 by an amount proportional to the stroke of the pump, means to displace the chart and the marker with regard to each other transversely to said last displacement by an amount proportional to the change in length of the pull rod between the 35 points of attachment for the chart and of the marker, and means to record said displacements on the chart by the marker.

3. In a device for recording the power of a reciprocating well pump comprising a pull rod 40 located in the well and a motor reciprocating said pull rod in the well and causing elastic changes in its length, a cylindrical chart and a marker in contact with each other and attached at spaced points to said pull rod, means for rotat- 45 ing the chart and the marker with regard to each other by an amount proportional to the stroke of the pump, means for displacing axially the chart and the marker with regard to each other by an amount proportional to the change in length of 50 the pull rod between the points of attachment of the chart and of the marker, and means for recording said rotational and axial displacements on the chart by the marker.

4. In a device for recording the power of a reciprocating well pump comprising a pull rod, 55 and a motor reciprocating said pull rod in the well and causing elastic changes in its length, a cylindrical chart attached to the pull rod, means to prevent the rotation of said chart around the 60 pull rod, a marker rotatably attached to the pull rod at a point spaced from the point of attachment of the chart, said chart and marker being in contact with each other, means for rotating the marker with regard to the chart by an amount 65 proportional to the stroke of the pump, means for axially displacing the chart and the marker with regard to each other by an amount proportional to the change in length of the pull rod between the points of attachment of the chart 70 and the marker, and means for recording said rotational and axial displacements on the chart by the marker.

5. In a device for recording the power of a

reciprocating pump located in a well and actuated by a pull rod, a cover tube rigidly mounted on the body of the pump around the lower end of said pull rod, a cylindrical chart supported by the lower end of said pull rod within said tube, means 5 to prevent the rotation of the chart with regard to the cover tube, a cylinder rotatably attached to the pull rod and movably fitting inside the cover tube, helical slots on the outside surface of said cylinder, a marker mounted on said cylinder, 10 said marker being in contact with said chart, lugs inwardly mounted on the cover tube and adapted to slide in said helical slots, and means comprising said lugs and said slots to rotate said cylinder with regard to the cover tube by the motion of 15 the pull rod.

6. In a device for recording over a plurality of operating cycles the power of a reciprocating well pump comprising a pull rod located in the well and a motor reciprocating said pull rod in the well 20 and causing elastic changes in its length, a chart and a marker supported by said pull rod, means for displacing during each pumping cycle the chart and the marker with regard to each other by an amount proportional to the stroke of the 25 pumps and for returning them to their original position, means for displacing during each cycle the chart and the marker with regard to each other transversely to the first named displacement by an amount proportional to the elastic change 30 in length of the pull rod, and for returning them to their original position, feeding means for continuously displacing the chart and the marker with regard to each other in an axial direction, and means for recording said displacements on 35 the chart by the marker.

7. In a device for continuously recording the power of a reciprocating pump located in a well and actuated by a pull rod, a cover tube rigidly mounted on the body of the pump around the 40 lower end of said pull rod, said lower end being provided with threads, a cylindrical chart supported on said threads within said tube, means to prevent the rotation of the chart with regard to the cover tube, a cylinder rotatably attached to 45 the pull rod and movably fitting inside said cover tube, helical slots on the outside surface of said cylinder, a marker mounted on said cylinder, said marker being in contact with said chart, lugs inwardly mounted on the cover tube and adapted 50 to slide in said helical slots, means comprising said lugs and said slots to rotate said cylinder with regard to said cover tube by the motion of the pull rod, and means to move the chart axially on the threaded part of the pull rod by rotating said pull rod.

8. In a device for recording the power of a reciprocating well pump comprising a pull-rod located below the well head and undergoing axial motion and elastic deformation, a chart and a 6 marker attached to said pull-rod and capable of relative motion with regard to each other, means responsive to the elastic deformation of the pull-rod to move the chart and the marker axially with regard to each other and to record the extent of said relative axial motion, means to translate the axial motion of the pull-rod into a transverse motion of the chart with regard to the marker, and to record the extent of said relative transverse motion.
